C. H. LEWIS

AUTOMOBILE SIGNAL

Filed April 7, 1922

UNITED STATES PATENT OFFICE.

CHARLES H. LEWIS, OF DENVER, COLORADO.

AUTOMOBILE SIGNAL.

Application filed April 7, 1922. Serial No. 550,430.

To all whom it may concern:

Be it known that I, CHARLES H. LEWIS, a citizen of the United States, and resident of the city and county of Denver, State of Colorado, have invented certain new and useful Improvements in Automobile Signals; and I do declare the following to be a full, clear, and exact description of the invention, such as will enable others skilled in the art to which it appertains to make and use the same, reference being had to the accompanying drawings, which form a part of this specification.

The object of this invention is to provide a simple and cheap means for signaling to pedestrians and other machines all the movements of an automobile in advance of the movements, either by day or by night.

Briefly the invention comprises a rotatable casing adapted to indicate movements to the right, left, forward and reverse, which is equally serviceable for both day and night driving, the casing being rotatable different amounts in different directions to show the proper signal. A control leads to the driver's seat and is manually operable for moving fingers selectively through varying ranges whereby the casing is rotated. The casing also carries a globe adapted to be illuminated to indicate an intention to stop or slow down.

In the accompanying drawings wherein certain embodiments of the invention are disclosed,

Fig. 1 is an elevation of the signal with parts broken away showing the face of the device as indicated by line 1—1;

Fig. 2 is an edge elevation as indicated by line 2—2;

Fig. 3 is a sectional detail taken on line 3—3 of Fig. 2;

Fig. 4 is an elevation of the control mounted on the steering post;

Fig. 5 is a perspective view of said control;

Fig. 6 is a diagrammatic showing of the various positions to be indicated by the device;

Fig. 7 shows the signal in position on an automobile;

Fig. 8 is a view indicated the mounting of the "stop" or "slow" signaling means.

The signal comprises a circular casing 10 which carries lenses 12 on its opposite sides by means of beads 14, said lenses being translucent and having arrows 15 delineated

thereon preferably in red and pointing in the same direction. One end of the casing carries overlapping tongues 16 and 18 between which the opposite end of the casing is received as seen best in Fig. 3. The outer tongue 18 has an ear 20 thereon which cooperates with an ear 22 on a tongue 23 on the other end of the casing, whereby the parts are maintained in assembled relation as by means of a bolt 24. A socket 25 for a light bulb B is carried on the inner tongue 16, and an electric conductor 26 leads through the casing to the socket. The outer tongue 18 carries a depending supporting sleeve 28 rotatably mounted upon a hollow stem 30 carried in a bracket 32 and secured therein as by means of a set screw 34. The bracket is in two sections pivotally connected at 35 for ready adjustment, and the inner end thereof fits over the upper end of a windshield post 36 or the like being retained thereon as by a set screw 38.

The casing is rotated through the medium of a flexible shaft 40 carried in a flexible housing 42 which passes upward through the hollow stem 30, the shaft 40 being secured to the casing at the base of the socket 25 as shown. Thus rotation of the shaft 40 will shift the signal to the various positions shown in Fig. 6. A globe 45 is provided upon the top of the casing 10, as seen in Figs. 6, 7 and 8, and has an electric cord 46 leading thereto within the casing as shown. A switch, not shown, is provided for controlling this light, and said switch may be operable manually, or through either the brake or clutch pedal. Preferably, this globe will be red, so that whenever contact is made, as by depressing the pedal, a red light will be shown to indicate that the driver is about to stop or slow down, and if desired the globe may carry the word "Stop" or the word "Slow." This globe, being on top of the casing, will be visible whatever the direction indicated by the casing.

The means for operating the flexible shaft 40 is mounted upon a bracket 52 carried by the post P which supports the steering wheel W. Within this bracket 52 the end of the shaft 40 is journaled adjacent one end, while at the other end it carries a suitable mounting 54. Upon the extremity of the shaft 40 a pair of arms 55 and 56 are journaled, these arms being connected by a spring 58 for returning them both into engagement

with a fixed pin projecting from the bracket 52 as shown at 60. An operating lever 62 is fixed to the shaft 40 for rotating the same and has a pin projecting therefrom at 64 directly in line with pin 60 so as to be positioned between the arms 55 and 56. Thus by moving the lever 62 in one direction, the shaft 40 will be correspondingly rotated and the respective arms 55 and 56 will be moved 10 so as to tension the spring 58 and insure return of the parts by said spring to normal position after release. The lever 62 is positioned in the vicinity of the circumference of the steering wheel W as seen in Fig. 7, 15 so that it may be easily manipulated without entirely removing the hand from the wheel.

In using the device, the casing will be set normally so that the arrows 15 will point 20 straight ahead and the small window 48 in the rear thereof will be seen, this window 48 preferably being red. By moving the lever 62 a quarter turn in one direction, the arrows will point to the left, while a quarter 25 turn in the opposite direction will cause the arrows to point to the right (Fig. 6). By turning the lever 62 a half turn, which may be accomplished readily by proper set of the bracket 52, the casing will be turned so 30 that the arrows 15 point to the rear and the small window 50 in the front of the casing, which is preferably green and normally is directed forward, now faces rearward. The spring 58 always returns the parts to normal 35 upon release of lever 62. "Stop" or "Slow" will be indicated by illuminating the globe 45.

I claim:

1. A signal comprising a casing rotatable 40 on a vertical axis, direction indicating means on opposite sides thereof pointing in the same direction with reference to the casing, said means normally pointing ahead, and means for rotating said casing through 90° 45 to indicate movement in either transverse direction and through 180° to indicate movement rearward, selectively.

2. A signal comprising a casing rotatable on a vertical axis, direction indicating means on opposite sides of said casing pointing in 50 the same direction and visible by day, an illuminating device to render said means visible by night, means to rotate said casing to indicate either transverse direction, and means adapted to be illuminated mounted 55 upon the top of said casing for indicating "stop".

3. A signal comprising a casing rotatable on a vertical axis, direction indicating means on opposite sides of said casing and visible 60 by day, an illuminating device for rendering the same visible by night, means to rotate the casing through 90° to indicate either transverse direction and through 180° to indicate reverse selectively, and means on the 65 front and rear of said casing when set in normal straight ahead position adapted to be illuminated to indicate front and rear at night.

4. A signal comprising a casing rotatable 70 on a vertical axis, the sides of said casing being translucent and having direction indicating means delineated thereon pointing in the same direction and visible by day, an illuminating device for rendering said means 75 visible by night, means for selectively rotating the casing to indicate either transverse direction, and means exteriorly mounted at the top of the casing and adapted to be illuminated for indicating "stop" at night. 80

5. A signal comprising a casing rotatable on a vertical axis, the sides of the casing being translucent and having direction indicating means delineated thereon which are 85 visible by day, an illuminating device with- in the casing for rendering said means visible by night, means for selectively moving said casing to indicate either transverse direction, and means permanently visible exteriorly mounted upon the casing and 90 adapted to be illuminated at night for indicating "stop".

In testimony whereof I affix my signature.
CHARLES H. LEWIS.
